FASTENING MEANS

Joseph Siegel, New York, N. Y.

Application February 8, 1944, Serial No. 521,500

2 Claims. (Cl. 24—77)

1

This invention relates to devices employed for attaching together the loose ends of a belt or strap, and more particularly to belt or strap buckles or clasps.

It is an object of the present invention to provide a buckle device which is capable of being easily and quickly attached to and detached from a strap or the like.

Another object of the present invention is to provide a buckle device which may be readily and securely but removably applied at or near one loose end of a strap without a sewing, stapling, riveting or like operation; and in such a manner as to render its accidental disconnection therefrom while in use practically impossible, since the means for connecting the buckle to the strap and after it has been applied thereto, is also employed for anchoring or catching the other loose end of the strap to the buckle.

Yet another object of the present invention is to provide a buckle having means only on the rear or back face thereof adapted to project through the strap for removably fastening it to an end thereof, which means is further adapted to engage the other end of the strap through an opening therein or loop thereof.

By providing the points of fastening of the buckle to the strap and of the loose end of the strap to the buckle behind the front face of the buckle, all fastening means and connections are concealed from view and the embellishment of the buckle is not impaired.

A still further object of the present invention is to provide in combination with a strap having at one end thereof perforations, a buckle having a stud and a hook projecting from the back face thereof and receivable in the said perforations, with the hook overlying the back of the strap and a loop connected to the other end of the strap and engageable with one of the projecting members of the buckle, whereby the buckle may be securely fastened to the strap and the loop held in engagement with the buckle.

A further object of the invention resides in the provision of a very simple, inexpensive, efficient, and durable buckle which may be readily and securely attached to a perforated end of a strap, the attaching means also providing an anchor for the securing of the other end of the strap.

Further objects and advantages of the invention will appear from the following disclosure thereof together with the attached drawing which illustrates certain forms of embodiment thereof. These forms are shown for the purpose of illustrating the invention, and it is to be un-

2

derstood that the instrumentalities of which the invention consists can be variously arranged and organized and that the invention is not limited to the precise arrangement and organization of the instrumentalities as herein shown and described:

In the drawing:

Fig. 1 is a front elevational view of a belt having disposed thereon a buckle made in accordance with the invention and shown in closed position;

Fig. 2 is a longitudinal-sectional view thereof taken along line 2—2 of Fig. 1;

Fig. 3 is a front elevational view of the buckle element;

Fig. 4 is an edge view of Fig. 3;

Fig. 5 is the rear view of Fig. 3;

Fig. 6 is a view of a locking loop used in connection with the buckle of Figs. 3 to 5;

Figs. 7 and 8 are front and side elevational views respectively of a retaining loop shown in Fig. 1;

Fig. 9 is a top plan view of a buckle embodying the invention in a modified form;

Fig. 10 is an edge view of Fig. 9 and showing the belt elements indicated in dot-dash lines;

Fig. 11 is an edge view of a buckle embodying the invention in a further modified form; and

Fig. 12 is a top plan view of Fig. 11.

Referring now more particularly to the drawing, there is disclosed a buckle member 15 and loop element 16, which may be made of any suitable material, such as, metal, plastic, composition, etc. Member 15 which may be of any suitable shape and design comprises a base or plate 17 from the back or rear face 18 of which projects near one end thereof a pin or stud 19 having a shank 19' and an enlarged head 20, and near the other end thereof an angular pin or tongue 21 having the rearwardly directed straight portion 20 or shank 22 connecting with plate 17 and the bent portion 23 spaced from the rear face 18 of plate 15 by portion 22 and preferably disposed substantially parallel with relation to the near face 18. It is preferable to have the bent portion 23 facing in a direction away from base plate 15, as shown in the drawing. The front face 24 of the plate 15 may carry suitable embellishment (not shown), or be suitably engraved or etched in a conventional manner, but not shown in the drawing.

Loop 16 may be formed from a single piece of material so shaped as to provide a longitudinal slot 25 and an eye 26.

Figs. 1 and 2 show the buckle and loop elements applied to a strap 28 such as of the type employed

as a belt, and having the conventional spaced eyes, perforations, or openings 21, 21', 21'', 21''' at one loose end portion 28' thereof. As very clearly seen in these figures, the buckle 15 is very easily, adjustably and readily and removably fastened to the strap by passing the angularly disposed pin or tongue 21 and the stud 20 respectively, through adjacent perforations 21', 21''. The bent portion 23 of tongue 21 overlies the rear face 29 of strap 28 constituting an abutment thereagainst.

The loop 16 is fastened to the other end of the strap by passing the loose end portion 30 through the longitudinal slot 25 of the loop 16 and securing portion 30 in overlying position to the adjacent portion 31 of the strap as by means of an eyelet or snap fastener 32.

As clearly seen in Fig. 2, the eye 26 of loop 16 is made to catch on or engage stud 19 between the rear face 29 of strap 28 and the enlarged head 20 of stud 19. The shank 19' is of sufficient length to accommodate the thickness of the strap 28 and loop 16.

It is evident that the girth of the strap may be varied simply by withdrawing the buckle 15 from the adjacent perforations 21', 21'' and replacing it on the strap by having the stud and tongue engage any other two perforations consecutive, adjacent, or otherwise.

The strap may be provided with one or more keeper loops 35 extending transversely across the strap for retaining the loose end portion 28' of the strap 28 in position.

Figs. 9 and 10 disclose a buckle 36 embodying the invention in a modified form. According to this embodiment, the buckle is provided with a hook-shaped member 37 projecting from the rear face of plate 39. It is preferred that member 37 be centrally disposed as regards the plate 39 and be of such shape that the pull on the strap when in operable position (see arrows A, B Fig. 10) will maintain the buckle flat against the strap. It is, therefore, proposed that the hook 37 have its bight 38 offset as regards its shank 40 which connects with plate 39. As seen in Fig. 10, the hook 37 is passed through a perforation of the strap at one end thereof and is adapted to be operatively engaged by the loop 16 on the other end of the strap.

Figs. 11 and 12 illustrate the invention in a further modified form as comprising a button-shaped buckle having a plate 40 from the rear face of which projects a stud 41 having a shank 42 and enlarged head 43. In adjusting the buckle onto the strap, stud 41 is made to engage one of the perforations in one end of the strap and the

eye or loop at the other end of the strap is made to operatively engage the stud in a manner similarly to that hereinabove described with respect to other embodiments of the invention, the enlarged head retaining the loop or eye against unfastening.

From the foregoing it can be readily understood that there has been provided herein an instrumentality or instrumentalities capable of fastening loose ends of a strap or other member and particularly utilizable as means for fastening together the ends of a belt, band, bracelet, wrist band or strap, garter, armband, etc., and providing an embellishment at the connecting ends.

Having thus described the invention, what I claim as new and desire to be secured by Letters Patent, is:

1. A buckle for a strap, comprising a plate and spaced-apart projections at the back of said plate, one of said projections extending from said plate intermediate its lateral sides and adjacent one end of said plate, said one of said projections being angular and having its free end projecting beyond said plate, the other of said projections comprising a stud extending from said plate intermediate its lateral sides and adjacent the other end of said plate, said stud comprising a shank and an enlarged head at its extremity, and a loop member adapted to be connected with an end of the strap and engaging said stud for securing portions of the strap together.

2. A buckle for attaching opposite end portions of a strap, comprising a plate adapted to be connected with one end portion of the strap and having spaced apart projections at the back of said plate to extend through openings in said end portion of the strap, one of said projections extending from said plate intermediate its lateral sides and adjacent one end of the plate and being angularly offset in a direction away from the opposite end of the plate to engage in one of the openings, the other of said projections comprising a stud extending from said plate intermediate its lateral sides and adjacent the other end of the plate, said stud including a shank and an enlarged head thereon at its extremity, and a loop member adapted to be connected with the opposite end portion of the strap and engaging said stud for securing the strap end portions together, said stud extending laterally from the plate a greater distance than the first-mentioned projection to extend through an opening in the strap and accommodate on the projecting extremity thereof the loop member.

JOSEPH SIEGEL.
